UNITED STATES PATENT OFFICE.

EUGENE W. MOCH, OF NEW YORK, N. Y.

FEATHER-TIP PIN.

SPECIFICATION forming part of Letters Patent No. 375,374, dated December 27, 1887.

Application filed June 28, 1887. Serial No. 242,719. (No model.)

To all whom it may concern:

Be it known that I, EUGENE W. MOCH, of New York city, New York, have invented a new and Improved Feather-Tip Pin, of which 5 the following is a specification.

This invention relates to a pin carrying a feather-tip. The pin is designed to be used as a hair-pin, hat-pin, corsage-pin, or the like.

The invention consists in the various features of improvement, more fully pointed out in the claim.

In the accompanying drawings, Figure 1 is a front view of my improved pin. Fig. 2 is a vertical central section thereof; and Fig. 3, a 15 transverse section on line $x-x$, Fig. 2.

The letter a represents a pin made of metal, ivory, turtle-shell, or of any other substance, and pointed at its lower end. At its upper or blunt end the pin a is provided with a socket, 20 a' , into which there are set the ends b^2 of quills b of preferably two ostrich-feather tips, b . The

exposed parts of the quills b are connected by threads c , while the parts b^2 , within the socket a' are left disconnected, so that they may spread and hold themselves in place. In this way 25 the feather-tips are properly secured to the pin; but, if desired, they may be additionally fastened by a suitable adhesive.

A feather-tip pin made according to my invention will be found to be strong and useful 30 to ladies for a variety of purposes.

What I claim is—

The combination of pin a , having socket a' , with feather-tips b , having quills b held in the socket a' , the upper end of quills b being connected by threads c , and the lower ends, b^2 , of such quills remaining disconnected, substantially as specified. 35

E. W. MOCH.
